UNITED STATES PATENT OFFICE

ROBERT B. CAMPBELL, OF MUSKEGON HEIGHTS, MICHIGAN, ASSIGNOR TO DESMOND MANUFACTURING COMPANY, OF MUSKEGON HEIGHTS, MICHIGAN, A CORPORATION OF MICHIGAN

SPRINKLING APPARATUS

Application filed June 21, 1929. Serial No. 372,557.

This invention relates to sprinkling apparatus of the character shown in the pending applications of John E. Desmond, Serial #364,483, filed May 20, 1929, and is directed 5 to improvements thereon, whereby it is possible to use the hose in the ordinary manner by closing the openings at spaced distances in the length of a hose where sprinkler heads are designed to be secured, or the device 10 may be used in the manner as described in said pending application by closing the flow of water at the outer end of the hose and having it dispensed through the sprinkler heads located at spaced parts points in the 15 length of the hose.

It is a primary object and purpose of the present invention to provide a hose with 20 sprinkler head attachments at spaced distances in the length of the hose, together with detachable means for maintaining the hose in a position such that the sprinkler heads will extend upwardly therefrom, and to detachably secure the sprinkler heads to the hose so that they can be detached at 25 will and the connecting sleeves to which they are detachably connected remain with the hose, to be closed at their outer ends so as to prevent any loss of water, thereby permitting use of the hose in the usual and 30 ordinary manner for the dispensing of water at the outer end thereof; and the stabilizing devices which are used to hold the hose in a position such that the sprinkler heads extend upwardly therefrom, may remain connected to the hose or be detached 35 therefrom when the sprinkler heads are removed, and the connecting sleeves therefor closed at their outer ends.

An understanding of the invention will be 40 had from the following description, taken in connection with the accompanying drawings, in which:

Fig. 1 is a plan of one of the sprinkler units, constructed in accordance with my invention, a plurality of which may be connected to the hose in the length thereof and at spaced distances.

Fig. 2 is a vertical section through the 45 hose substantially on the plane of line 2—2 of Fig. 1.

Fig. 3 is a fragmentary enlarged vertical section through the hose and the sprinkler unit attached thereto.

Fig. 4 is a transverse section through the 55 hose on the same plane as that shown in Fig. 3, but with the sprinkler head, and the holding or stabilizing device therefor removed and with the connecting sleeve for the sprinkler head closed at its outer end, and

Fig. 5 is a perspective view of a different 60 form of closing element which may be used to close the outer end of said connecting sleeve.

Like reference characters refer to like 65 parts in the different figures of the drawings.

The hose 1, of any ordinary construction, such as used for watering lawns and the like, is designed to have a plurality of sprinkler heads secured thereto at spaced distances in 70 the length of the hose and at the upper side thereof. For the purpose of holding the hose against turning or twisting and to maintain the sprinkler heads, when attached, in substantially vertical positions, holding 75 devices are connected with the hose at or adjacent the points of connection of the sprinkler heads. Said holding devices preferably are made of sheet metal and each is formed midway between its ends with a concave seat 2, in which the lower part of the hose may be located. At each side of the seat 2, the device is extended outwardly providing the horizontal ledges 3, and beyond the ledges the elongated arms 4, which are suitably ribbed lengthwise for strength 80 and reinforcement and which have upwardly turned end portions to eliminate any danger of digging into the ground. A clamp 5 is located over the hose and at its opposite 85 sides has outwardly extended flanges 6 which lie above the ledges 3.

The clamp is connected with said ledges 3 by means of bolts 7, fully shown in Fig. 3, which pass through said flanges 6, and ledges 3, as shown. It is evident that by removing the bolts 7, the parts described can be readily detached from the hose at any time it is desired.

In practice the upper side of the clamp 5, 100

is provided with an opening 8, and this opening is around a smaller opening in the upper side of the hose 1. A connecting sleeve 9 extends through the opening in the 5 hose and upwardly through the opening 8 in the clamp 5 and has an enlarged head 10 at its lower end within the hose, between which and a nut 11 threaded onto the projecting end of the sleeve 9, the parts of the 10 hose around the opening therethrough are clamped, this serving to securely connect the sleeve to the hose. It is also evident that the clamp 5 may be disconnected from the hose without affecting the attachment of the 15 sleeve 9, as the opening 8 is large enough to receive the clamping nut 11 which is used.

The upper end of the sleeve 9 above the 20 nut 11, is reduced in diameter and threaded both interiorly and exteriorly. A sprinkler 20 unit consisting of a depending stem 13 and a sprinkler head 14 at the upper end thereof, is secured on the reduced section 12 of the sleeve described, the lower end of the stem 13 being interiorly threaded to screw over 25 the part 12.

When thus connected there is a direct passage 30 for water from the hose through the sleeve 9, and stem 13 to the sprinkler head; and with a number of these sprinkler heads 35 attached in the length of the hose at spaced intervals a large area may be simultaneously sprinkled. By a cable or other connection on the outer end of the hose it may be moved around to different positions when the hose 40 is to be changed to serve a different area.

In order to use the hose as a hose is ordinarily used it is merely necessary to unscrew the stems 13 and plug the outer ends of the sleeves 9. This can be done by using a 45 screw plug, such as 15, in the outer end of each sleeve 9 as shown in Fig. 4, or as an alternative, a closing cap 16 may be threaded over the reduced portion 12 of the sleeve 9, in place of the plug 15. And if the clamp 5 50 is removed by detaching the bolts 7, the hose is then in the condition a new hose would be, prior to any attachment of the sprinkler apparatus of this invention, except for the connecting sleeves 9 which have been attached and which are closed by the plugs 15 or the caps 16.

From the foregoing, it will be apparent 55 that the hose may be used with a plurality of sprinkler units attached at spaced distances in the length of the hose, the same as in the application of Desmond structure previously noted, or it can be changed from such condition for use in the ordinary manner that a hose is used, that is, for dispensing water at the outer end thereof. The construction for attaining these results, is simple and economical to make. The invention is defined in the appended claims 60 and is to be considered comprehensive of

all forms of structure coming within their scope.

I claim:

1. In a device as characterized, a length of 70 hose having an opening therethrough, an outlet sleeve mounted in said opening, means for permanently securing said sleeve in place, a sprinkler head detachably secured at the outer end of the outlet sleeve, a clamp fitting around the said means and additional 75 means to hold the clamp in place.

2. In a device of the class described, a length of hose having an opening in a side thereof, an outlet sleeve extending through 80 said opening, means for permanently securing the sleeve to the hose whereby the outer end of the sleeve extends beyond the outer side of the hose, said outer end of the sleeve being reduced in diameter and screw threaded interiorly and exteriorly and a sprinkler 85 head detachably threaded onto the outer end of said sleeve whereby the same may be readily removed to permit closure of said outlet sleeve by means of a plug adapted to be threaded into the said sleeve for the purpose 90 described.

3. In a construction of the class described, a length of hose having an opening through 95 its upper side, a holding bar located transversely across and under the hose, a clamp extending over the hose, means for detachably connecting the clamp to said holding bar, an outlet sleeve mounted in said opening in the hose and extending through the clamp, means for securing said sleeve in permanent relation to the hose whereby said clamp and the holding bar may be removed without affecting said outlet sleeve, and a sprinkler head detachably secured at the outer end of the outlet sleeve whereby it may 100 be removed therefrom to permit closing said outlet sleeve to stop passage of water therethrough.

In testimony whereof I affix my signature.

ROBERT B. CAMPBELL.
